CLAIM

The ornamental design for a four cell food tray, as shown and described.

DESCRIPTION

FIG. 1 is a top plan view of a four cell food tray showing our new design;

FIG. 2 is a front elevational view thereof; the rear elevational view being a mirror image thereof;

FIG. 3 is a left side elevational view thereof; the right side elevational view being a mirror image thereof;

FIG. 4 is a bottom plan view thereof; and,

FIG. 5 is a sectional elevational view thereof; taken along line 5—5 of FIG. 1.

FIG. 1

FIG. 2

FIG. 3

FIG. 4

FIG. 5
